UNITED STATES PATENT OFFICE.

ADOLF KLEIN, OF VIENNA, AUSTRIA-HUNGARY.

OIL-BURNER.

986,067.

Specification of Letters Patent.

Patented Mar. 7, 1911.

Original application filed January 6, 1909, Serial No. 470,915. Divided and this application filed October 22, 1909. Serial No. 523,938.

To all whom it may concern:

Be it known that I, ADOLF KLEIN, a citizen of Austria-Hungary, and a resident of Vienna, in the Province of Lower Austria and Empire of Austria-Hungary, have invented certain new and useful Improvements in Oil-Burners, of which the following is a specification.

The present invention relates to oil burners adapted to economically utilize the caloric value.

The feature of the invention is to consume the crude oil by exposing it to progressive heating in such a manner that the various products of distillation or decomposition correspondingly progressively separate, first the very volatile, light products, then the less volatile, heavy and subsequently the very heavy products, and are burned in the order of their generation as stated in the specification which forms part of my application Serial No. 470,915 filed January 6th 1909, of which application this is a division.

25 In the annexed drawings: Figure 1 is a vertical section of a burner with a central channel for supplying combustible from above. Fig. 2 is a horizontal section of the burner along line A—B of Fig. 1, and Fig. 30 3 a top view of the middle portion of the burner, said figure being in part a section along the irregular line C—D of Fig. 1.

The burner shown in Figs. 1-3 consists of a distributing block 1 with stepped annular distributing spaces 4, 5, 6, for the centrally supplied combustible. These annular spaces are formed by partitions 9, and are in communication with one another by apertures 8 which are not in alignment with each other. The outermost annular space 6 is in communication with an annular distributing channel 12, which debouches into the combustion space 19 by means of transverse passages 13. The heat generated by combustion and radiated to the distributing block 1, so effects a gradual decomposition of the centrally supplied combustible, that the most volatile products separate in the innermost space 4, the less volatile or heavier products decompose in the successive annular spaces 5, 6 in accordance with their volatilization temperatures, until finally the heaviest products arrive at the burner cup 7. By virtue of the interconnection of the va-

rious, annular spaces mutually and with the combustion space, the products separated out can immediately burn in the order of their generation and the heat radiated therefrom on the one hand provides for the heating of the distributing spaces and on the other hand also for the heating of the heaviest products in the cup 7 and finally for heating the air necessary for supporting combustion. The air for combustion flows to the burner from below through an orifice 15 and is conducted through a distributing chamber 16 to the heating space 17. This space 17 is formed by the upper portion 3 of the burner and an annular partition 20 both of which are composed of good heat conducting material, and is in communication, by apertures 18 provided in the latter, with the combustion space 19. By this arrangement the air is conducted to the combustion space with a plurality of changes of direction, a change of velocity occurring with each change of direction, the air thus being thoroughly and uniformly heated.

The part 2 of the burner covers the spaces 4, 5 and 6 for distributing the fuel, whereas part 3 incloses the air heating space 17. Part 3 is provided with orifices 14, through which the various products of combustion escape in the condition of flame. By the upper portion 3 of the burner covering the combustion space, the temperature is effectively maintained so low that the heaviest products of decomposition which are contained in the cup 7 do not char.

90 The upper portion 3 of the burner carries a combustible supply conduit 2, through the bore 10 of which the combustible flows to the innermost distributing space 4. Inasmuch as the combustible should be supplied at as relatively low a temperature as possible to the situation where it is consumed, the conduit 2 for supplying the combustible is formed by a substance badly conductive of heat and for the same reason the distributing block 1 is likewise formed of a similar substance, for example fire-proof clay, chamotte, graphite, magnesite, asbestos, or a mixture of two or more of these materials.

95 In order to supply the air for combustion to the combustion space in an as highly heated condition as possible and thus pre-

vent the heavy products of decomposition contained in the cup 7 from being cooled to below their ignition temperature, the portions of the burner which conduct the air 5 as well as the upper portion 3 of the burner which contains the orifices 14, are constructed of a good conductor of heat, for instance metal. In order to conserve the heat thus stored in the metallic portions, 10 solely for the purpose of heating the air and combustible, the upper portion 3 of the burner is completely covered with a substance 21 badly conductive of heat.

I claim:

- 15 1. A burner for burning crude oil, comprising a block having a plurality of concentric annular distributing spaces adapted to receive and conduct the liquid fuel, annular partitions separating said spaces and having apertures providing communication between said spaces, and a fuel supply conduit covering the said spaces and adapted to conduct liquid fuel to the burner from above,

2. A burner for burning crude oil, comprising a block having a plurality of concentric annular distributing spaces, adapted to progressively conduct the liquid fuel, annular partitions separating said spaces and 30 having apertures providing communication between said spaces, a central fuel supply conduit covering said spaces and adapted to conduct the liquid fuel to the innermost space from above, a chamber for supplying 35 air centrally from below and an annular air heating space connecting the said air chamber with the combustion space of the burner.

Signed at Vienna in the Province of 40
Lower Austria and Empire of Austria-Hungary.

ADOLF KLEIN.
